US00D802206S

(12) **United States Design Patent** (10) **Patent No.:** **US D802,206 S**
Huang et al. (45) **Date of Patent:** **** Nov. 7, 2017**

(54) **ELECTRONIC VAPORIZER**

(71) Applicants: **Devin Huang**, Shenzhen (CN);
Handsome Zheng, Shenzhen (CN);
Emanuel Lau, Shenzhen (CN); **Ray Long**, Shenzhen (CN)

(72) Inventors: **Devin Huang**, Shenzhen (CN);
Handsome Zheng, Shenzhen (CN);
Emanuel Lau, Shenzhen (CN); **Ray Long**, Shenzhen (CN)

(73) Assignee: **ATMOS NATION LLC**, Davie, FL (US)

(**) Term: **15 Years**

(21) Appl. No.: **29/553,565**

(22) Filed: **Feb. 3, 2016**

(51) LOC (10) Cl. **27-01**

(52) U.S. Cl.

USPC **D27/101**

(58) **Field of Classification Search**

USPC D27/100, 101, 162, 163–169, 172, 175, D27/186, 189, 193, 194, 195, 136, 137, D27/138

CLAIM

The ornamental design for an electronic vaporizer, as shown and described.

DESCRIPTION

FIG. 1 is a right front perspective view for an electronic vaporizer, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict unclaimed subject matter of the design and form no part of the claimed design.

1 Claim, 7 Drawing Sheets
